UNITED STATES PATENT OFFICE.

CHARLES P. STANBON, OF LYNN, MASSACHUSETTS, ASSIGNOR TO UNITED SHOE MACHINERY COMPANY, OF PATERSON, NEW JERSEY, A CORPORATION OF NEW JERSEY.

HEELING-MACHINE ATTACHMENT.

1,098,693.

Specification of Letters Patent.

Patented June 2, 1914.

Application filed August 12, 1912. Serial No. 714,754.

To all whom it may concern:

Be it known that I, CHARLES P. STANBON, a citizen of the United States, residing at Lynn, in the county of Essex and State of 5 Massachusetts, have invented an Improvement in Heeling-Machine Attachments, of which the following description, in connection with the accompanying drawings, is a specification, like letters on the drawings 10 representing like parts.

The invention to be hereinafter described relates to machines for treating the heels of boots and shoes, and more especially to means for applying an adhesive to the heel 15 seat prior to the application of the heel thereto.

In attaching heels to boots and shoes, nails or other fasteners are usually driven through the heel into the heel seat, and 20 prior to thus securing the heel to the boot or shoe, it is desirable that an adhesive be interposed between the heel seat and the heel to thus provide a close joint or union between the two.

25 To effectively secure the desired results in these respects, the present invention aims to provide means which shall be simple in construction, and so operated during the action of the heel nailing or attaching machine that a fresh surface or film of adhesive 30 shall be automatically presented in convenient and readily accessible position for the operative to apply the same to the heel seat as he passes the boot or shoe to the heel 35 nailing devices.

The accompanying drawings exemplify one practical form of the invention, wherein a brush is mounted to rotate in a box or tank containing a quantity of the adhesive, and is 40 given rotative movement by means connected to the heel nailing devices, so that as the heels are successively secured to the boots or shoes, the brush is rotated to lift from the tank or box a fresh quantity of 45 the adhesive for application to each heel seat, all as will hereinafter more fully appear.

In the drawings: Figure 1 represents in 50 partial side elevation and section, a portion of a heeling machine containing the present invention; and Fig. 2 is an enlarged section on the line 2—2, Fig. 1.

For exploitation purposes the invention is shown as applied to a heeling machine of 55 the general type disclosed in the patent of

T. G. Plant, No. 958,292, dated May 17, 1910, but it is obviously adapted for use in connection with any machine where heels are attached to boots and shoes.

The machine frame for supporting the operative parts may be of any preferred form or type such for instance, as indicated in the said Plant patent, only so much thereof being illustrated as is necessary to disclose the association of the present invention therewith. The machine frame has the side uprights or parts 1, preferably having top flanges 2 which act as guides for side rods or plungers 3, to which the cross-head and heel nailing devices are or may be connected, said rods or plungers having bifurcated lower portions 4, embracing the shaft 5 on which are secured suitable cams 6 acting upon pins or rolls 7 projecting from the side rods or plungers 3, the construction being such that upon rotation of the shaft 5, the cams 6 of which there are preferably two, one at each side of the machine to contact with associated side rods or plungers, will cause the cross-head and nailing devices to be operated substantially as set forth in the said Plant patent to which reference may be had.

Extending from the machine frame is a bracket 8 which may be secured thereto by appropriate means for the support of a tank or box in which is contained the adhesive to be applied to the heel seat. As shown in the drawing the bracket 8 and tank 9 are integrally formed, but this is not essential. 90

The side portions 10 of the tank 9 are provided with bearings for the support of the brush shaft 11, and as shown these bearings may be formed by slots 12 in the side portions 10 of the tank to permit ready removal of the brush shaft. To maintain the brush shaft properly seated in its bearings, hooks 13 are pivoted at 14 to the sides of the tank and have finger portions 15 which extend over the end portions of the brush 100 shaft when the latter is in its bearings.

The brush shaft 11 has secured thereto in any appropriate manner to rotate therewith, a brush 16, the lower portion of which passes into the adhesive 17 as the brush may be rotated, as will presently appear, and carries a fresh supply or film of adhesive into position for convenient application to the heel seat of a shoe by an operative standing in front of the machine. Secured to the brush shaft 110

11 is a ratchet wheel 18 in co-operative relation to a pawl 19 connected at 20 with the pawl operating means, shown as a slide 21. Projecting from the bracket 8 at the side 5 thereof is a web or flange 22, the outer end portion of which extends downward at 23 and is perforated at this part to form a bearing for the slide 21. The slide 21 is further guided in its longitudinal movement by passing through a suitable opening in the bracket 8 and flange 24 of the side upright 1, as at 25, and its end, at the right, Fig. 1, projects into the path of movement of a part connected to the nailing mechanism, whereby upon operation 10 of the nailing mechanism as pointed out by the Plant patent hereinbefore mentioned, the slide 21 may have imparted to it movement to cause the pawl 19 and ratchet 18 to turn the brush shaft, and perforce, the brush 20 secured thereto. As an appropriate means to these ends, the side rod 3 which actuates the nailing devices, has adjustably secured to it by means, such as the set screw 26, a collar 27 having a cam projection 28 adapt- 25 ed to meet and force the slide rod 21 to the left, Fig. 1, as the rod 3 descends in operating the nailing devices. The adjustable connection of the collar 27 to the side rod 3 may be made by any suitable means, the slot 29 and set screw 26, being a simple and convenient form of such means.

The end 30 of the slide rod 21 is preferably pivoted to the main portion of the slide rod, as at 31, and is capable of turning upward into dotted line position but incapable of turning downward farther than shown by full lines, Fig. 1, the construction being such that as the side rod carries the cam portion 28 of the collar 27 past the end of the 35 slide it will push said slide longitudinally to the left, Fig. 1, but on the upward movement of the side rod 3, the end 30 of the slide will yield upward without imparting longitudinal movement to the slide.

40 In order to move the slide 21 to the right after having been moved to the left in the manner stated, the said slide is under the influence of a spring 32, one end of which bears against the part 23 and the opposite 45 end of which is seated upon a collar 33 secured to the slide. While the means described forms a simple and convenient expedient for operating the ratchet through the pawl 19, it is obvious that other means will 50 readily suggest themselves to those skilled in the art for turning the brush 16 by connections with the heel nailing means. In order to prevent rotative movement of the slide 21, a key 34 extends into a suitable key-way 55 in the slide, and a spring 35 normally acts upon the pawl 19 to hold it in operative relation with the ratchet 18.

The adhesive contained in the tank 9 is, or may be fugitive in character, that is to 60 say, it readily evaporates and becomes thick

when exposed to the air, and to obviate this objection when the machine is at rest, a cover 36 is hinged to the supporting bracket at 37 whereby it may be readily turned up when the adhesive is to be used and then as readily turned down to close the tank when the machine is not to be operated, the cover 36 at such times serving to close the top of the tank throughout its length.

From the construction described it will be noted that a simple and efficient device is employed, convenient to the hand of the operative, for the application of adhesive to the heel seats of boots and shoes immediately prior to attaching the heel thereto, and that the brush is rotated to expose suitable quantities of adhesive fresh from the tank by connections with the heel nailing means, and while the described details furnish a good and convenient form of such means, it is to be understood that they may be varied within the true scope of the invention which is definitely set forth by the claims.

What is claimed is:—

1. In a machine for attaching heels to boots and shoes, the combination of a tank for containing an adhesive, means for supporting the tank at the front and side of the machine frame, a brush mounted in fixed position at the front and side of the machine frame to dip into said tank, devices for rotating the brush in its fixed position to expose a supply of adhesive for application to the heel seat of a boot or shoe by the operative at the front of the machine and prior to attaching the heel thereto, heel nailing means, and means connected to the heel nailing means for actuating said devices.

2. In a machine for attaching heels to boots and shoes, the combination of a tank for containing an adhesive, means for supporting the tank at the front and side of the machine frame, a brush in fixed position at the front and side of the machine frame mounted to dip into said tank, ratchet and pawl devices for rotating the brush in said fixed position to expose a supply of adhesive for hand application by the operative to the heel seat of a boot or shoe prior to attaching the heel thereto, heel nailing means, and means connected to the heel nailing means for actuating said devices.

3. In a machine for attaching heels to boots and shoes, the combination of a rotary brush supported in fixed position at the front and side of the machine frame, means for supplying an adhesive to said brush for hand application to the heel seat of a boot or shoe prior to attaching the heel thereto, actuating means for heel attaching devices, and means operated by movement of said actuating means for rotating said brush in its fixed position at the front and side of the machine frame.

4. In a device of the character described, the combination of the machine frame, a tank for holding adhesive supported thereby, a rotary brush mounted in fixed position and dipping into said tank, heel nailing means, and means actuated from said heel nailing means for rotating said brush and comprising a slide having a knuckle jointed end portion, and a reciprocating cam for acting on said end portion to cause the slide to move when the cam travels in one direction and permitting the slide to remain at rest when the cam travels in the opposite direction.

15 5. In a heel nailing machine, the combination of a main frame, a tank for holding an adhesive to be applied by the operative to the heel seat of a boot or shoe prior to attaching a heel thereto, a rotary brush mounted in fixed position and dipping into said tank, means including a slide for rotating the brush in its fixed position, a reciprocating rod, and a cam adjustably connected to said rod and coacting with said slide.

20 6. In a heel nailing machine, the combination of a main frame, a tank for holding an adhesive to be applied to the heel seat of a shoe prior to attaching the heel thereto, a rotary brush mounted in fixed position and dipping in said tank, a ratchet and pawl for rotating said brush to expose fresh portions thereof to the operative, heel nailing means, and cam devices actuated from and by movement of the heel nailing means for operating the ratchet and pawl to thereby rotate the brush in its fixed position.

25 7. In a heel nailing machine, the combina-

tion of a main frame, a tank for holding an adhesive and supported at the front and side of the main frame for the operative to apply adhesive to the heel seat of a boot or shoe prior to attaching the heel, a rotary brush mounted in fixed position and dipping into said tank, a slide mounted at the side of the tank, connections between the slide and brush for rotating the latter in its fixed position upon reciprocation of the slide, nailing devices, a reciprocating slide rod connected thereto, and a cam or tappet carried by said rod to engage and move the slide as the rod moves in one direction.

30 8. In a heel nailing machine, the combination of a main frame, a tank for holding an adhesive and supported at the front and side of the main frame for the operative to apply adhesive to the heel seat of a boot or shoe prior to attaching the heel, a rotary brush mounted in fixed position and dipping into said tank, a slide mounted at the side of the tank, connections between the slide and brush for rotating the latter in its fixed position upon reciprocation of the slide, nailing devices, a reciprocating slide rod connected thereto, a cam or tappet carried by said rod to engage and move the slide as the rod moves in one direction, and means to prevent rotary movement of the slide.

35 In testimony whereof, I have signed my name to this specification, in the presence of two subscribing witnesses.
